UNITED STATES PATENT OFFICE

2,523,593

FROSTED FOOD CABINET

Charles S. Raffa, New York, N. Y.

Application June 30, 1947, Serial No. 758,189

2 Claims. (Cl. 62—89.5)

1

The present invention relates to improvements in refrigerated cabinets, particularly those of the so-called walk-in type commonly used for the storage of perishable merchandise such as food products.

It has heretofore been the practice to use the walk-in refrigerators for storage purposes and to provide separate, individually refrigerated display cases wherein the merchandise would be visible to the customers. The storage capacity of such cases is necessarily small, since the shelves must be well spaced and arranged so as to afford a convenient view of the goods and since the width of the case is limited by the need for accessibility of all the goods to the salesman. The provision of separate cooling systems is uneconomical, particularly in view of the fact that the case must be opened at frequent intervals during sales as well as for the purpose of reloading the shelves with merchandise taken from the storage cabinet.

The principal object of the present invention is to provide a refrigerated cabinet for the storage of large quantities of merchandise and for the simultaneous display of a selected portion thereof, a common cooling system being utilized for this purpose.

Another object of the invention is to provide a refrigerated cabinet of the walk-in type having a special section adapted as a showcase, this section being accessible both from the outside and from within the storage cabinet.

Additional objects and features will become apparent in the course of the following description, taken in conjunction with the accompanying drawing, in which:

Fig. 1 is a front elevation of a part of a cabinet according to the invention.

Fig. 2 is a cross-section taken on line 2—2 of Fig. 1.

Fig. 3 is a sectional elevation on line 3—3 of Fig. 2.

Fig. 4 is an illustration of a detail on a larger scale.

Fig. 5 is a sectional view taken along line 5—5 of Fig. 4.

Referring first to Figs. 1, 2 and 3, the cabinet generally indicated at 10 comprises a storage chamber 11, accessible through the walk-in door 12, and a showcase 13 where merchandise stored on shelves 14 is displayed through the sliding glass doors 15. The doors 15 may be slightly inclined to afford better visibility, as seen in Fig. 3, and may comprise two or more transparent front panels 16 to provide adequate heat insula-

2

tion. The main storage or working chamber 11 is obscured from view of the customers by back doors 17 which may be slidable, in similar manner as front doors 15, by mechanism presently to be described. The doors 17 may each comprise a simple panel 18 of metal or other preferably opaque material, to provide a suitable background for the goods displayed on the shelves 14, and should have no thermal insulation so as to expose the showcase 13 to the temperature obtaining in chamber 11.

The customer, standing in front of the glass doors 15, may observe the goods on display, and the customer may be served from these doors.

15 The doors 17 may be conveniently operated by a person standing on the floor 19 of the aisle adjoining the walk-in door 12, in order to reload the display shelves with merchandise. The shelves 20 are open toward the aisle for replenishment of merchandise and accessible from without through the hinged doors 21 for service to customers.

The sliding doors 15 and 17 are arranged in pairs, each pair comprising two doors located in different planes and displaceable in opposite directions. Adjacent pairs are separated by jamb members 22 to which are secured brackets 23 supporting the shelves 14 and 20. The members 22 also serve as intermediate supports for a rail 24 which extends across the cabinet and carries the back doors 17 so that they may freely slide between flanges 25 and 26; the upper end of these doors is sustained by depending flanges 27 and 28 of a co-extensive rail 29, the top of which is positioned above the lintel of the front doors 15. Similarly, the front doors 15 are supported between upstanding flanges 30 and 31 and depending flanges 32 and 33 forming part of the front wall 34 of the cabinet 10.

40 Spaced along the rail 24 are pairs of casters 35 which are carried by shafts 36 and are rotatable thereon by means of roller bearings 37 (see Figs. 4 and 5). These casters are disposed in mortise-shaped recesses 38 and may have a crowned surface designed to cooperate with a corresponding concave surface on the lower sash portion 39 or doors 17. In the embodiment illustrated, six pairs of casters are provided for each pair of back doors 17; similarly, six pairs of 45 casters 40 are disposed between flanges 30 and 31 for each pair of front doors 15. Thus, the doors may be readily displaced, and any desired section of the showcase may be opened from either inside or outside the cabinet.

50 Since the compartment 13 is exposed to ambi-

ent temperatures on one side only, and in open communication with compartment 11, above and below the partition formed by the doors 17 and their frames, its loss of refrigeration will be small compared to the heat transfer taking place between conventional display cases and the atmosphere. Thus, if an existing walk-in cabinet is to be converted into a combined storage and display cabinet according to the invention, the required fractional increase in the output of the common cooling plant will be small relative to the cost of operation of a separate refrigeration unit for the showcase alone.

It will thus be seen that workmen, as for instance butchers, may be at work preparing cuts of meat in the refrigerator storage and work-room 11 without being visible to customers viewing merchandise in the display case 13 while the display case is maintained at substantially the same low temperature as the compartment 11 of which it is actually a part.

While I have shown a preferred embodiment of my invention, it is to be understood that modifications and adaptations may be made without departure from the spirit and scope of the invention as defined in the appended claims.

Having thus described my invention, what I claim as new and desire to secure by Letters Patent, is:

1. A refrigerated cabinet of the walk-in type having a door for a person to enter, a compartment disposed along one side of said cabinet in substantially breast height of said person, one or

more manually slideable inner doors separating said compartment from the rest of the cabinet, one or more manually slideable transparent doors separating said compartment from the outer atmosphere, said transparent doors being thermally insulated, a plurality of shelves within said compartment, and a plurality of shelves underneath said compartment, said latter shelves being accessible from the outside through one or more hinged doors.

5. A cabinet as set forth in claim 1, wherein said inner doors are non-transparent and thermally conductive and wherein said hinged doors are non-transparent and thermally insulated.

15 CHARLES S. RAFFA.
